UNITED STATES PATENT OFFICE.

GOTTLOB FUEGEL AND HERMAN SCHMID, OF BROOKLYN, NEW YORK, ASSIGNEES, BY
MESNE ASSIGNMENTS, TO APOLLO MAGNETO CORPORATION, OF BROOKLYN, NEW
YORK, A CORPORATION OF DELAWARE.

LUBRICATING DEVICE.

1,421,681.

Specification of Letters Patent.

Patented July 4, 1922.

Original application filed December 27, 1918, Serial No. 268,554. Divided and this application filed
August 30, 1919. Serial No. 320,912.

To all whom it may concern:

Be it known that we, GOTTLÖB FUEGEL and HERMAN SCHMID, who were formerly subjects of the German Empire, but who 5 have severally renounced all allegiance to said power and declared our intentions of becoming citizens of the United States, being therefore advised that at present we are not citizens of any country, residing in 10 Brooklyn, in the county of Kings and State of New York, have invented certain new and useful Improvements in Lubricating Devices, of which the following is a specification. 15 Our invention relates to improvements in lubricating devices; particularly lubricating devices to be employed in connection with bearings for shafts that require to have the positions of their axes varied. 20 Our invention is especially adapted for use on magnetos that supply electric current to the igniters or spark-plugs of internal combustion engines; and our principal object is to lubricate the adjustable bearing of 25 the shaft of the distributor mechanism of an ignition magneto when such bearing is provided to enable said shaft to be moved towards or from the axis of the armature of the magneto, and thus render the distributor 30 shaft capable of turning at a relatively greater or smaller number of revolutions per minute; so that the magneto can be utilized, without alteration of any of its parts, except the distributor mechanism, upon engines 35 having a larger or smaller number of cylinders.

A further object of our invention is to provide a lubricating device which is intended for the adjustable bearing of the distributor shaft of an ignition magneto; and which is designed to lubricate said shaft most efficiently in all the adjusted positions of said shaft or the parts of the bearing carrying same. 45 Other objects and advantages of our invention will be set out in the following description, taken with the accompanying drawings; and the characteristics of our invention will be precisely defined in the appended claims. The disclosure, however, is 50 illustrative only, and other embodiments may be resorted to, within the scope and spirit of our invention, as the same is ex-

pressed in the claims, and within the general meanings of the terms employed in the 55 phrasing of the same.

On the drawings:

Figure 1 is a vertical longitudinal sectional view through the front end of a magneto showing an adjustable bearing for the 60 distributor shaft and a lubricating device for same according to our invention;

Figure 2 is a section taken on the line 2-2 of Figure 1;

Figures 3, 4 and 5 are respectively a front 65 elevation, a side elevation and a rear elevation of a bushing that is part of our invention;

Figures 6, 7 and 8 are respectively a front 70 elevation, a side elevation and a rear elevation of an eccentric sleeve to be employed in connection with said bushing; and

Figure 9 is a view showing an element for absorbing the lubricating agent employed 75 in the practice of our invention.

The same numerals identify the same parts throughout.

This application is a division of our prior co-pending application Serial No. 268554 80 for a patent on adjustable bearings, filed December 27th, 1918, and is restricted to features of construction whereby efficient lubrication is secured.

In Figure 1 we show at 1 a portion of a magneto for the electric ignition of an internal combustion engine. This magneto comprises among other things a rotatable armature, not shown, carrying a gear indicated in part at 2 meshing with a distributor gear 3; and all of the parts of the magneto, 85 including the casing indicated in outline at 4 for the gear 3, will be suitably mounted by means of a frame work or housing. The casing 4 will be held in place by securing the same to a support 6 which is on the 90 housing 1 and in which our adjustable bearing is disposed. In practice the armature, which will rotate on an axis parallel to the gear 3 and carry the gear 2 to drive the gear 3, as stated, will be provided with a low 95 tension or primary winding and a high tension or secondary winding; and will include a timer for breaking the circuit of the primary winding and a distributor for supplying the high tension or secondary current to 100 the spark-plugs or igniters of the engine 105

cylinders. We do not illustrate either the timer or the distributor mechanism here, as the general construction and mode of operation of the same and of the entire magneto are well known; and the distributor mechanism always includes a rotating contact which is carried by the gear 3 and completes the circuit to each spark-plug in succession as the gear 3 turns. For a four cylinder engine the gear 3 must be twice as large as the gear 2 and therefore rotates at one-half the speed of the latter; while for six cylinders, the gear 3 must be three times the size of the gear 2 and therefore rotates at one-third the speed thereof. Hence if the magneto is to be changed so as to adapt it for a six cylinder engine instead of a four cylinder engine, the distance between the axis of rotation of the gear 3 and the axis of the armature must be altered. If for example, the gear 3 is twice as big as the gear 2 and rotates at one-half the speed of the gear 2 and we wish to have the gear rotate at one-third of the speed of the armature, we preferably attain our object by replacing the gear 2 with a slightly smaller gear and the gear 3 with a slightly larger one. Such a change involves the replacing of the casing 4 with a slightly larger casing and the moving of the axis of rotation of the gear 3 farther away or upward from the axis of the armature. If, on the other hand, the gear 3 is three times as big as the gear 2 and rotates at one-third the speed of the gear 2 and we desire to have it rotate only one-half the speed of the armature we proceed accordingly by mounting on the armature a little larger gear 2 and choosing a little smaller gear 3 and casing 4, and moving the axis of the gear 3 downward towards the axis of the armature to the required extent. The casing 4 is of course held to the support 6 by means of fastening devices which can be easily removed to enable a suitable gear casing to be easily put on or taken off, and our adjustable bearing, mounted in the support 6, permits the location of the axis of the gear 3 at the necessary distance from the axis of the armature in a manner now to be described.

As shown in Figures 1 and 2, the support 6 has an aperture 7 therethrough. This aperture 7 is elongated vertically and it receives a bushing 8 which has an eccentric opening 9. This bushing is inserted into the aperture 7 from the rear; that is, from the face of the support 6 opposite to that which abuts against the casing 4; and the opening 9 receives an eccentric sleeve 10 which has an eccentric bore 11 for the shaft or journal 12 of the gear 3. Owing to the shape of the aperture 7 and the configuration of the bushing 8, the axis of the shaft 12 can be located closer to or farther from the axis of the armature, according to the

position of the bushing 8 in the support 6. As shown in Figures 1 and 2, the axis of the gear 3 is a certain distance from the axis of the armature, but if the bushing were reversed or inverted in the aperture 7, the axis of the gear 3 would be moved farther away from the armature axis. As indicated in Figure 1, the bushing 8 terminates short of the front face of the support 6; while the sleeve 10 extends all the way through this bushing and beyond the front end of the aperture 7, and even goes through the central opening of the casing 4 for the shaft 12 and may abut against the rear face of the gear 3. In either position of the bushing 8, the sleeve 10 can be turned in the opening 9 to move the gear 3 into the most efficient operative position in order to make the teeth of the gear 3 and the gear 2 go into proper mesh with one another. 85

As Figure 2 shows, the aperture 7 is rounded at the top and bottom and flat at the sides. Therefore it is symmetrical as regards both its longitudinal or vertical axis, and its transverse or horizontal axis. The body of the bushing 8 has the same shape and therefore may be described as symmetrical in the same respects, and as having rounded ends or portions 13 and flat sides 14. On one face it has a flange 15, which, when the bushing 95 is in the aperture 7, will fit against the rear of the support 6. Of course the opening 9 is circular.

The sleeve 10 is circular on its outer face and has polygonal flange 16 at its rear end 100 to enable the same to be turned in the opening 9. At its opposite end it is counter-sunk or recessed to provide a shoulder 17 around the edge of the bore 11 to receive a washer 18, which is held on the shaft 12 between the rear face of the gear 3 and a shoulder on the shaft; and the sleeve 10 will preferably fit against this washer so that end play or axial movement of the gear 3 is prevented.

The bushing 8 is provided in one of its 110 rounded portions 13 with a groove 19 and likewise with a recess 20 in the opposite rounded portion. When the bushing is in the aperture 7, this groove and this recess will be engaged by fastening means, such as 115 bolts 21 which pass through passages extending from side to side of the support 6. Hence the displacement of the bushing from the support is prevented. The lower recess 20 goes through the body of the bushing and 120 communicates with the opening 9; and the sleeve 10 has a peripheral recess or groove 22 which is engaged by one of the bolts 21; such bolt projecting laterally through the recess 20 into the groove 22, and axial movement of the sleeve 10 is likewise prevented. To reverse or invert the bushing the bolts 21 are removed, and replaced when the reversal or inversion is effected. The bolts 21 125 may be roughened where they engage the 130

grooves 19 and 22, to make them hold the bushing and sleeve securely.

The top of the casing 4 will have an oil opening 23; from which leads a duct 24 which will register with a space 25 in the support 6 leading to the space in front of the bushing 8. In the lower end of the aperture 7, just in front of the bushing 8, we provide an oil groove or channel 26 and in 10 this groove we place a body of absorbent material such as a segment of felt 27, shown in Figures 1, 2 and 9. The oil which passes down into the space in front of the bushing 8 will saturate the body 27 and any excess 15 will collect in the groove 26. The body 27 will make contact with the outside of the sleeve 10, and we preferably provide in the plane of contact and at equal intervals apart three holes 28 which lead through from the 20 outside of the bushing 10 to the bore 11. These holes may be filled with fibrous material to form wicks and the oil from the body 27 will soak through these wicks and spread over the inside of the sleeve 10 and the outside 25 of the shaft 12, thus lubricating the gear thoroughly.

The shaft 12 is held in the sleeve 10 by any suitable means to engage its rear end.

By the above construction we are enabled 30 to use the same magneto for either four or six cylinder engines merely by changing the gears 2 and 3, with the shaft 12, together with the casing 4 and distributor plate which carries the high tension binding posts. At 35 the same time efficient lubrication is obtained under all conditions.

When oil is poured into the opening 23, it either drips upon the sleeve 10 and saturates the wicks in the holes 28, or it runs down 40 the sides of the opening 8 into the groove or recess 26 and saturates the felt 27. At least one of the wicks will always be in contact

with the upper edge of the felt 27, which will be compressed by the sleeve 10, as indicated by the broken curved line in Figure 9, and 45 lubrication for all positions of the shaft 12 is thus assured.

Having described our invention, what we believe to be new and desire to secure and protect by Letters Patent of the United States is:

1. The combination of a support having an aperture and a recess in said aperture, an eccentric sleeve in said support to engage a shaft, absorbent material in said recess and 55 engaging said sleeve, said sleeve having holes therethrough containing absorbent material to make contact with the absorbent material in the recess and conduct lubricant to the inside of the sleeve. 60

2. As an article of manufacture, an eccentric sleeve having a bore therethrough and holes to admit lubricant to the inside of said sleeve, and absorbent material filling said holes. 65

3. The combination of an adjustable bearing sleeve, and a body of absorbent material to be saturated with lubricant and make contact with said sleeve, the latter having openings to enable lubricant from said absorbent 70 material to penetrate to the inside of said sleeve.

4. As an article of manufacture, a sleeve having an eccentric bore and having one end recessed and a polygonal flange on the other 75 end, said sleeve also having an external groove to be engaged by fastening means, and having one or more holes therethrough to admit lubricant to its interior.

In testimony whereof, we have signed our 80 names to this specification this 22nd day of May, 1919.

GOTTLOB FUEGEL.
HERMAN SCHMID.
